UNITED STATES PATENT OFFICE.

FRED C. KRUEGER, OF PRINCETON, WISCONSIN.

TWISTING IMPLEMENT.

Application filed January 31, 1923. Serial No. 616,135.

To all whom it may concern:

Be it known that I, FRED C. KRUEGER, a citizen of the United States, residing at Princeton, in the county of Green Lake 5 and State of Wisconsin, have invented certain new and useful Improvements in Twisting Implements; and I do hereby declare the following to be a full, clear, and exact description of the invention, such as 10 will enable others skilled in the art to which it appertains to make and use the same.

This invention relates to a twisting implement of the general class used in connection with the splicing of wires.

It is aimed to provide such an instrument particularly useful for linemen and adapted to twist the usual sleeves with the wires in such a manner as to eliminate 20 mutilation thereof to an extent affecting their efficiency.

Other objects are to provide a construction by the use of which the wires may be efficiently stretched, one in which the parts 25 are adjustable to efficiently receive, hold and release the sleeve and wires, and one having novel relatively fixed and movable means to effect the twisting.

Still another object is to provide a construction embodying the various details, combinations and arrangements of the parts comprising the embodiment set forth in accompanying drawings.

Various additional objects and advantages will be pointed out and become apparent from a consideration of said drawings in connection with the following description.

In said drawings:

Figure 1 is a perspective view of the implement;

Figure 2 is a perspective view of the twisting head;

Figure 3 is a plan view on a reduced scale 45 suggesting the actual use of the implement;

Figure 4 is a substantially central longitudinal sectional view on the line 4—4 of Figure 1;

Figure 5 is a cross sectional view on the 50 line 5—5 of Figure 1;

Figure 6 is a cross sectional view on the line 6—6 of Figure 1;

Figure 7 is a detail perspective view of

one of the bearing members employed for the twisting head, and

Figure 8 is a longitudinal sectional view substantially similar to Figure 4 but on a smaller scale and showing wires and a sleeve in place for twisting.

Like reference characters designate like 60 or similar parts in the different views.

Referring specifically to the drawings, a cylinder or barrel is provided at 10 having a longitudinal slot 11 extending from end to end thereof. Associated with the barrel 65 are attaching heads 12 and 13. The head 12 may consist of a ring 14 and arms 15 of any suitable number, integral therewith, and integral with or fastened to the barrel 10. Head 13 consists of a ring 16, a collar 70 17 of the same diameter as barrel 10, and arms 18 preferably integral with ring 16 and collar 17. Collar 17 has an elongated slot 18' extending from end to end thereof and alining with the slot 11.

Disposed within the barrel 10 and collar 17 at the facing ends thereof, are ring bearings 19, fixed in place as by means of set screws 20 passed through said barrel and sleeve, respectively. In one face of the 80 rings 19, balls or other bearings 21 are journaled and said rings 19 have outwardly flaring slots 22 in alinement with slots 11 and 18'.

A twisting head or reel 23 as particularly detailed in Figure 2, has a stub shaft 24 journaled in the rings 19 and at each end of which disks 25 are rigidly provided thereon. The facing surfaces of said disks 25 engage the balls 21 with a view to reducing friction incidental to turning of the head 23 through the manipulation of a handle or arm 26 extending rigidly from the stub shaft 24. Also, the twisting head 23 at both disks 25 and shaft 24 has an outwardly flaring slot 27, capable of registration with the slots 11, 18' and 22. It will be realized that the fastening of the rings 19 in place also secures the twisting head 90 or reel 23 and the barrel 10 and attaching head 13 in place.

In the outer end of the barrel 10, a disk 28 is fitted having an outwardly flaring slot 29 in registry with the slot 11. Disk 28 is slidable longitudinally within the barrel 10 to the extent permitted by pins 30 radi-

ating from and through elongated slots 31 provided through the barrel 10. Exterioly of the barrel and in spaced relation to its periphery, a band 32 is fastened to form a means of engagement to readily slide said disk 28. Band 32 is slotted as at 33 in line with the slot 29.

The inner extremity of slot 29 is 8-shaped as at 34, and in longitudinal alinement therewith, the inner extremity of the slot 27 is 8-shaped as at 35. Shoulders 34^a and 35^a are provided in slots 34 and 35, respectively.

One example of the use of the tool is given in Figure 3. In that figure, the ends of wires to be joined are designated *a* and *b*. In joining them, preferably the usual 8-shaped coupling sleeve *c* of the same thickness as shoulders 34^a and 35^a is utilized and with the size of which sleeve, cross-sectionally, the slots 34 and 35 correspond. A wire grip *d* may be attached to the ring 16 and also rigidly to the wire *a*. A block *e* may be attached to the ring 14 and carry a pulley *f* over which a cable or flexible element *g* is trained. One end of cable *g* is preferably anchored independently of wire *b*. Wires *a* and *b* may be entered in their adjacent terminals in the sleeve *c* and with the disk 28 at the maximum distance from the adjacent disk 25. Such sleeve *c* is inserted through the slot 11 with the wires *a* and *b* accommodated in the slots 11, 18', 27, 29, 34 and 35. When the sleeve *c* is so positioned, it will be at the axis of the barrel and one end thereof may be slipped into the slot 35 while sliding movement of disk 28 toward the adjacent disk 25 will cause the other end of said sleeve to be received in the slot 34. Sleeve *c* engages shoulders 34^a and 35^a so as to be held against danger of longitudinal displacement. Upon the free end of cable *g* being pulled, the wire *a* will be tensioned, and by means of pliers or another tool the wire will be tensioned so that it will enter the sleeve *c* to the maximum extent. With the sleeve *c* and wires *a* and *b* coupled as suggested, handle 26 is rotated a suitable number of times which will cause rotation of the head 23 with respect to the disk 28 which remains relatively stationary and whereby the terminals of the wires and the sleeves *c* will be effectively twisted together. It will be realized that during the entire twisting and coupling operation, that the sleeves and wires are accommodated in the various slots substantially at the longitudinal center of the implement. After the twisting operation, the disk 28, through manipulation of band 32, may be slid away from the twisting head, in order to release the sleeve *c* and thus enable the wires *a* and *b* and sleeve *c* to be disengaged from the tool. The flaring of the slots 27, 22 and 29, facilitates entrance of the wires.

It will be understood that other methods of use of the tool will be obvious and that it may be used in different arts from that stated, and for instance in connection with the stretching and splicing of said wires.

I claim as my invention:

1. A twisting implement having a barrel, a twisting head turnable with respect to the barrel, a disk non-rotatable with respect to the barrel and adapted to engage the work in connection with said head, said barrel having an elongated slot, and said disk being slidable and having a pin extending through said slot and exteriorly beyond the slot for engagement to operate the disk.

2. A twisting implement having a barrel, a work holding means on said barrel, a twisting head for the work movable with respect to the barrel, said barrel, head and means being slotted to enable wires to be substantially disposed at the axis of the barrel, and the inner extremities of the slots of said means and head being shaped to accommodate a wire-splicing sleeve and to provide shoulders for engagement with the end edges of the sleeve.

3. A twisting implement having a barrel, a work holding means on said barrel, a twisting head for the work movable with respect to the barrel, said barrel, head and means being slotted to enable wires to be substantially disposed at the axis of the barrel, the inner extremities of the slots of said means and head being shaped to accommodate a wire-splicing sleeve and to provide shoulders for engagement by the end edges of said sleeve, and said means being movable longitudinally of the barrel to facilitate engagement and disengagement of the sleeve.

4. A twisting implement having a barrel, a disk slidable in said barrel, said barrel having slots, pins extending through said slots, a band rigid with said pins exteriorly of the barrel, said band, barrel and disk having alined slots to accommodate the work, and a twisting head movable relatively to said barrel.

5. A twisting implement having a twisting head provided with a stub shaft, a barrel, a disk on said stub shaft disposed within the barrel, a bearing for said stub shaft carried by the barrel, a handle extending from the stub shaft, said bearing being located intermediate the handle and disk, and holding means for the work carried by said barrel.

6. A twisting implement having a barrel and an attaching head provided with a collar, a twisting head having a stub shaft, disks rigid with said stub shaft and disposed one at each end thereof and one within the barrel and one within the collar, a manipulating handle extending from said shaft, bearings for said shaft located be-

- between said handle and said disk, and said bearings being fixed on to the barrel and one to the collar, and holding means for the work carried by the barrel.
- 5 7. A twisting implement having a barrel, an attaching head having a collar, said barrel and collar having aligned longitudinally extending slots, a twisting head including a stub shaft, disks rigid with said stub
- 10 shafts and located one at each end thereof and one within the barrel and one within the collar, bearings fastened on to the barrel and one to the collar intermediate said disks, an operating handle extending from
- 15 said stub shaft intermediate said bearings, said disks, stub shafts and bearings having

slots registering with said slots, a slideable head within the barrel having a slot registering with the slot thereof, said barrel having a plurality of elongated slots, pins extending from the slideable disk through the last mentioned slot, a band exteriorly of the barrel and rigid with said pins, and said band having a slot in registry with the first mentioned slot of the barrel. 20 25

In testimony whereof I affix my signature in presence of two witnesses.
